UNITED STATES PATENT OFFICE.

HERMAN R. KOESTER, OF BOND HILL, OHIO, ASSIGNOR TO THE PHILIP CAREY MANUFACTURING COMPANY, A CORPORATION OF OHIO.

EXPANSION JOINT.

Application filed December 3, 1920. Serial No. 427,844.

To all whom it may concern:

Be it known that I, HERMAN R. KOESTER, a citizen of the United States, and a resident of Bond Hill, in the county of Hamilton, 5 State of Ohio (whose post-office address is Yarmouth and Oberlin Avenues, Bond Hill, Cincinnati, Ohio), have invented new and useful Improvements in Expansion Joints, of which the following is a specification.

10 My invention relates to an improvement in expansion joints for use in highways, concrete or otherwise. Heretofore in the use of expansion joints, more especially expansion joints formed of a bituminous material, or a bituminous compound and a supporting or reinforcing material, it has been found that when in place the adjacent ends did not retain their positions. The adjacent ends would tilt in opposite directions, 15 would overlap, one remain vertical and the other tilt at an angle thereto, etc. This gave dissatisfaction, tending to disrupt the pavement when expanding, etc. Attempts have been made to overcome these objections by making the joints longer but due to the 20 nature of the material these attempts have not proven satisfactory. I have discovered that these defects and objections may be overcome by making expansion joints of 25 two or more sections provided at the ends with means, either separate or integral with the sections, for supporting the adjacent ends in contact and in alignment so that each two or more sections of joint are substantially 30 one and the position of one joint at the end is the same position as the end of the next adjacent joint.

In the drawings in which like letters refer to like parts:

35 Fig. 1 is a top view of two sections of an expansion joint showing one form of my invention.

Fig. 2 is a top view of Fig. 1 showing the joint ready to be installed.

40 Fig. 3 is a side view of Fig. 2.

Fig. 4 is a cross section of Fig. 2.

Figures 5, 6, 7, 8, 9, 10, 11, 12 and 13 are 45 modifications of my invention.

Referring to the drawings I have shown 50 therein my invention applied to expansion joints using the form of expansion joints in which a bituminous material and a reinforcing material is used but I would have it understood that my invention is equally applicable to other forms of expansion joints 55

wherein similar difficulties are met with. In the drawings A is a bituminous compound, preferably asphalt and any suitable filler, B, B is a reinforcing material preferably felt saturated or impregnated, depending upon the felt used, with an asphalt. Such expansion joints are shown in U. S. Patent No. 1,339,094 to Ford C. Bowman and form no part of my invention. These joints in the preferred form of my invention I attach to each other at their adjacent ends, by cementing with any suitable cement D, although I prefer a waterproof cement such as an asphalt cement, strips C, C of flexible material such as a strip of felt saturated with asphalt or similar material saturated or impregnated with a bituminous material. These strips C, C are preferably arranged on both sides of the adjacent sections of expansion joint and may be attached thereto by cement D as stated, or may be stapled by staples E, E or by both cement and staples. To enable ready handling and transportation of these joints I apply the strips C, C at the factory, leaving one end of one strip 80 C free from one side of the end of one of the joint strips as shown in Fig. 1. This enables the joints to be folded upon one another for shipment. The strips C, C by reason of the nature of the material, it being a felt saturated or impregnated with asphalt, is flexible and elastic and readily acts as a hinge while at the same time it also corresponds in action with the joint under movement of the pavement due to expansion and contraction resulting from temperature changes. In some forms of joint the bituminous material A extends above the reinforcement B and in such case I prefer to leave the strips C, C of substantially 85 the same width as the reinforcing member B. When the joint has arrived on the job and is about to be installed the workmen then coat the free end of the strip C with cement D and placing the adjacent ends of 90 the joint together the free end of the strip C is pressed against the strip B of the joint so as to cement the strip C in place as shown in Fig. 2 after which the staples E, E are driven in. Of course the cement could here 95 again be dispensed with, and only staples used or staples omitted and cement only used. If desired the workmen could also put some cement between the adjacent ends of 100 the joints where they touch to cement them 105

and prevent any objectionable spaces. The strip C could be placed on one side only of the joints in which event, on the job, the workman would merely have to unfold the 5 adjacent sections of joint.

In the modification shown in Fig. 5 I have shown a joint with a felt or metal strip C in the center of one end of one section of expansion joint and attached to the outer 10 surface of the next adjacent section. In Fig. 6, I have shown a metal strip C embedded in the end of one section of joint and adapted to be forced into the next section. In Fig. 7, I have shown a similar modification except that in place of being embedded into the joint the strip C is formed at one 15 end so as to enclose two or more sides of the end of one section of the joint and the other end of the strip C is adapted to be forced into the adjacent end of the next section of 20 joint.

In Figures 8 and 9 the modification is in the form of a channel C which encloses two 25 sides of the ends of adjacent sections of joint and the bottom thereof. In this modification the channel C may be either metal, saturated felt, impregnated felt or any suitable material adapted to withstand the wearing conditions equally with the joint proper.

30 In all the modifications shown in Figs. 5 to 9 inclusive, as well as in the preferred form shown in Figures 1 to 4, the attaching means for holding the joints together may be attached to one or both adjacent sections 35 of the joint by either cement, or staples or both or in any suitable manner.

In Figures 10, 11, 12 and 13, I have shown a modification of my invention in which I use metal plates F having teeth G, stamped 40 out of the metal or formed at the ends of the plates by turning up the metal, adapted to be pressed into the sections of joint to support same in desired position. The teeth G may be of varying length or shape and 45 either integral with or separate from the

plate F. If separate any suitable staples or other means may be used for holding it in place.

What I claim—

1. An expansion joint comprising a plurality of sections composed of a plastic mass and a strip of flexible waterproof material connecting adjacent ends of same. 54
2. An expansion joint comprising a plurality of sections and a waterproof hinge 55 connecting adjacent ends of same.
3. An expansion joint comprising a plurality of sections composed in part of a mass of plastic material and a separate strip of flexible material connecting adjacent ends of 60 same.
4. An expansion joint comprising a plurality of sections composed in part of a mass of plastic material and separate means connecting adjacent ends of same, and means 65 for attaching the aforesaid means to said sections.
5. An expansion joint composed of a plurality of sections of board like plastic material and means independent of but fixedly 70 attached to one of said sections for holding the adjacent end of the next section in alignment with each other.
6. An expansion joint composed of a plurality of sections of board like plastic material and means arranged on each side of 75 said sections and fixedly attached to one of the two abutting sections for holding the adjacent ends of said sections in alignment 80 with each other.

7. An expansion joint formed of a plurality of separate sections of plastic waterproof material and means fixedly attached to one of the two abutting sections for holding the 85 adjacent ends of said sections together so as to retain said adjacent sections in alignment.

In testimony whereof, I have signed my name to this specification.

HERMAN R. KOESTER.
